UNITED STATES PATENT OFFICE.

CHARLES H. OCUMPAUGH, OF ROCHESTER, NEW YORK.

INDEPENDENT-VOTING MECHANISM.

1,003,645.

Specification of Letters Patent. Patented Sept. 19, 1911.

Original application filed December 7, 1903, Serial No. 184,187. Divided and this application filed March 12, 1904, Serial No. 197,834. Renewed April 20, 1911. Serial No. 622,326.

To all whom it may concern:

Be it known that I, CHARLES H. OCUMPAUGH, a resident of Rochester, in the county of Monroe and State of New York, have invented certain new and useful Improvements in Independent-Voting Mechanism; and I do hereby declare the following to be a full, clear, and exact description of the invention, such as will enable others skilled in the art to which it pertains to make and use the same.

The invention relates to independent or irregular vote mechanism, and has for its object to provide efficient, convenient, certainly acting and economical devices for voting for unnominated candidates.

The invention consists in the construction hereinafter described and pointed out.

In the accompanying drawing, Figure 1 is a broken horizontal section of a machine showing the upper ends of paper rolls or spools; Fig. 2 is a broken section on line 2—2 of Fig. 1; Fig. 3 is a view of an end plate of a spool-supporting frame showing the situation of the irregular resetting bar after disengaging a pinion holding pawl; Fig. 4 is a perspective of an interlocking-bar-indicator-cover-and-rack, a resetting bar being also indicated; Fig. 5 is a horizontal section of abutment-holding bars of the interlocking mechanism, interlocking bars being shown in plan; Fig. 6 is an elevation of an interlocking and lockout mechanism, the abutment-holding bars being omitted; Fig. 7 is a broken vertical section showing a part of the means for actuating the resetting bars; Fig. 8 is a transverse section showing resetting bars and a part of the actuating mechanism; and Fig. 9 is a perspective of a paper spool diagrammatic in character showing means for connecting paper thereto. Fig. 10 illustrates the position of parts shown in Fig. 3 before the actuation of the irregular resetting bar.

The invention has been embodied in a machine such as described in my application #184,187 filed Dec. 7, 1903, of which application the present is a division.

Numeral 1 denotes the machine case and 2 its front plate having openings 6 to receive the keys or indicators 3^x attached to plates 5 which normally cover the said openings. One of these covers is normally situated immediately in front of a platen 7 that supports paper against a pen or pencil

while the voter is inscribing the name of his candidate. This particular plate is provided with a rack 5^x and is connected to an interlocking strap 17^a having a thickened part 18^x situated on the opposite side of bars 19, the parts being so disposed that a movement of the plate 5 sufficient to uncover the opening 6 to give access to the platen 7 draws the said part 18^x between the bars 19. These bars are provided with abutments 20 so situated as to coöperate with the thickened ends 18 of other key straps 17 and effect an interlocking of the vote indicators. The straps 17 having the regular voting keys 3 are bent adjacent the bars 19 alternately in opposite directions, their thickened interlocking ends being denoted by 18. The irregular straps 17^a have necessarily a longer stroke than the regular straps to provide for uncovering the openings 6 and unlike the regular straps have no angle at their interlocking ends, but are so formed as to avoid contact with a lockout resetting bar 65. The straps 17^a are situated at one side of a resetting bar 86 for 80 the straps 17.

55 and 56 denote paper-holding spools, paper being drawn from 56 and wound onto 55.

Either a regular indicator key 3 and strap 17 or an irregular key 3^x and strap 17^a can be moved but not both at the same time because of interlocking. As stated the irregular cover 5 is provided with a rack (see Figs. 1 and 4). When a cover is moved to the right, the rack meshes with and moves a long pinion 41, without, however, moving pinion 52, which is held from movement by its pawl; the reverse movement of the cover, rack and pinion 41 (which can be only caused by movement of the resetting bar 95^x), by means of pinion 52, idler 53 and pinion 54 turns a spool 55 and winds thereon a portion of a web of paper which web has one end attached to the spool 55 and the other to a spool 56. Between the two spools the paper passes across the platen arranged with its face in a plane parallel with, directly behind, and close to the openings 6 which are exposed when the covers 5 are suitably moved. On a portion of paper which passes over the platen adjacent an opening, the voter is allowed to write his choice of a candidate for any office represented by an indicator. It will be noted 110

that the cover 5 extends to the left of the opening 6 and when moved to the right will continue to substantially cover the opening until the rack has passed the pinion, so that 5 the paper has ceased its movement by the time the cover has been moved sufficiently to permit the writing of a candidate's name.

In the present instance there are two pairs 10 of spools, one pair situated above the other, and each pair provided with a long pinion 41. Each of the two long pinions coöperate with a pinion 52 to drive a spool pinion 54 by means of an intermediate gear or idler 53.

15 In order to reduce the cost of replenishing the paper, it is divided into two webs, one for the upper part of the machine, and the other for the lower. Each web of paper has two spools, one for the blank paper 20 and the other for winding thereon the recorded votes. The axes of the two spools for the blank paper are coincident and the two spools for receiving the recorded votes also have their axes coincident. There are 25 also two long pinions corresponding with the spools, and the axes of these are coincident. (See Fig. 2.)

There is usually but little irregular voting 30 for the higher offices such as governor, lieutenant governor, etc., it being much greater for local offices, since candidates for such offices are usually personally known to the voter. In my present arrangement this latter class of offices is represented by the 35 lower part of the face plate of the machine, and by appropriate paper-holding spools so that the web-holding spool for local offices can be separately replenished while for the 40 majority of elections the upper web-holding spool of paper will not need replenishing.

Each of the paper rolls is rotatably supported by suitable trunnions in a frame comprising plates 57 and 58 joined by bars 45 49 and platen 7. The shaft of pinion 41 is journaled in the same plates and has on one end a pinion 52 which through an intermediate gear 53 drives another pinion 54 fast on the paper spool or roll shaft 55 50 which is thereby adapted to wind the paper from roll 56. The pinions 52 and 41 have a ratchet connection as indicated.

55 93 indicates a pawl pivoted at 97 and normally pressed by a spring 98 to hold it engaged with the pinion 52 and prevent 60 rotating the paper rolls with the effect to move fresh paper in front of the platen until the bar 95* is reset by the outgoing voter. 99 denotes a pawl extension or loop whereby said pawl may be disengaged from 65 the pinion 52 by means of the arm 100 carried by the bar 95*. This permits another voter to move the cover 5 and by means of the rack 5* move the paper rolls. When 65 the cover is moved to uncover opening 6,

the pawl 96, normally held engaged with pinion 52 by spring 98, holds said pinion against movement until such time as the spring is overcome and the pawl disengaged. This is effected by the outgoing voter 70 by means of the irregular resetting bar 95* and its connections. At such time the arm 100 fixed to said bar underruns a part 99 connected to the pawl and lifts it out of engagement with the pinion. The 75 arm 100 in the instance illustrated has a suitable shoulder or bend that is moved against the pawl 99 to throw it out of engagement with the pinion. It will be understood that the long pinion 41 is returned 80 by the rack 56 fixed to the cover and indicator without moving pinion 52, the ratchet clutches indicated at 102 being of suitable form, as indicated, to permit such return.

95* (see Fig. 4) denotes a resetting bar 85 movable by means of devices including a turnstile construction having an arm such as indicated at 40 in Fig. 7 which can be moved to rotate a short shaft having a gear 25. This gear by means of a coacting gear 90 26 rotates a shaft 24 operatively connected by intermediate devices, not shown, with a shaft 77 which has fixed thereon a cam disk 95 adapted to move a connecting rod 89, arm 94, link 95 and resetting bar 95*. 95

86 denotes a resetting bar for the regular and question vote indicators. It extends through slots in the straps connected to said indicators and is operated by a turnstile or the like meditately rotating shaft 100 77 having a cam disk to actuate said bar by suitable intermediate mechanism.

65 denotes a resetting bar for official lock-out devices and is operated from the same shaft 77 by appropriate connections. These 105 latter resetting bars and other related mechanisms are set forth in my application 184,187, filed Dec. 7, 1903, and need no further description herein.

Having thus described my invention, 110 what I claim as new and desire to secure by Letters Patent, is;

1. In a voting machine, a regular indicator and interlocking strap, and an irregular indicator and cover-plate having an 115 interlocking strap positively attached thereto, the two classes of straps interlocking one with the other and having two different lengths of travel at the interlocking point. 120

2. In a voting machine, a face plate having an opening, an indicator, a cover for said opening and connected to the indicator, a rack bar attached to the indicator, a pinion engaging with the rack, and devices 125 whereby the pinion when moved in one direction is automatically locked against return.

3. In a voting machine, a face plate having an opening, an indicator, a cover for 130

7 said opening and connected to the indicator, a rack bar attached to the indicator, a pinion engaging with the rack, devices whereby the pinion when moved in one direction is automatically locked against return, and means to unlock the pinion and return the plate and indicator.

8 4. In a voting machine, a face plate having an opening, an indicator, a cover for 10 said opening and connected to the indicator, a rack bar attached to the indicator, a pinion engaging with the rack, devices whereby the pinion when moved in one direction is automatically locked against return, and means to unlock the pinion and return the plate and indicator, said means 15 comprising a resetting bar.

5. In a voting machine, regular indicators, irregular indicators, a resetting bar for 20 the regular indicators, a resetting bar for the irregular indicators, and means for actuating said bars by the outgoing voter, the movement of the irregular resetting bar being greater than that of the regular resetting bar.

25 6. In a voting machine, regular indicators each connected to an interlocking bar, and an irregular indicator connected to a bar interlocking with the regular bars, the irregular indicator and bar traveling oppositely to the regular to effect interlocking therewith.

30 7. In a voting machine, irregular vote indicators, a resetting bar, a plurality of pairs of spools, one of each pair being aligned with one of another pair, connections between the indicators and spools including a pair of pinions for each pair of spools, and a clutch connection between each pair of 40 pinions whereby one or both may be driven according as an indicator or the resetting bar is moved.

45 8. In a voting machine, an elongated pinion, a paper spool and connections between the two, including two ratchet gears in mesh, the movement of the pinion in one direction only turning the paper spool.

50 9. In a voting machine, a casing, an irregular vote-receiving mechanism including an elongated pinion, cover plates and a resetting bar for the cover plates, the bar in its movement passing between the pinion and the casing.

55 10. In a voting machine, an irregular vote-receiving mechanism containing a pinion, a plurality of cover-plates, and a rack bar attached to each plate and capable of engaging with the said pinion, but in its normal position disengaged therefrom.

60 11. In a voting machine, an irregular vote-receiving mechanism containing a pinion, a plurality of cover-plates, a rack bar attached to each plate and capable of engaging with the pinion but in both its normal and actuated 65 position disengaged therefrom.

12. In a voting machine, a pinion, an irregular cover-plate having an interlocking strap attached thereto, a rack bar attached to the cover and engaging the pinion to move it in one direction, means for automatically locking the pinion when thus moved, and devices for unlocking the pinion and returning the cover plate. 70

13. In a voting machine having a face plate, means for casting a vote by writing, 75 comprising an opening in the face plate, a platen adjacent the opening, mechanism for moving paper across the platen, a cover indicator for said opening, means for positively moving the cover from the opening, 80 and an interlocking bar continuously fixed to the cover, said interlocking bar being in line with said cover and directly moved thereby.

14. In a voting machine having a face 85 plate, means for casting a vote by writing, comprising an opening in the face plate, a platen adjacent the opening, mechanism for moving paper across the platen, a cover indicator for said opening, means for positively moving the cover from the opening, 90 an interlocking device fixed to the cover, said device being in line with the cover and directly reciprocated thereby, and a resetting device for the cover and interlocking 95 device.

15. In a voting machine having a face plate, means for casting a vote by writing comprising an opening in the face plate, a platen adjacent the opening, mechanism for 100 moving paper across the platen, a cover indicator for said opening, means for positively moving the cover from the opening, an interlocking device continuously fixed to the cover, said device being in line with the 105 cover and directly reciprocated thereby, and a resetting device for the cover and interlocking device.

16. In a voting machine having a face plate, means for casting a vote by writing, 110 comprising an opening in the face plate, a platen adjacent the opening, and mechanism for moving paper across the platen, said paper-moving mechanism being directly actuated by the indicator cover, and comprising 115 a rack fixed to the cover and meshing with a pinion, said pinion also meshing with a pinion on a paper-roll spool.

17. In a voting machine having a face plate, means for casting a vote by writing comprising an opening in the face plate, a cover for said opening, a paper support, a platen adjacent the opening, mechanism directly and positively connecting the cover and paper support for moving paper across the 125 platen and including a driving device rigidly fixed to and directly movable with said cover, and a device to prevent return movement of the mechanism.

18. In a voting machine having a face 130

plate, means for voting by writing, comprising an opening in said face plate, a platen adjacent the opening, mechanism for moving paper across the platen, said mechanism comprising a paper-delivering spool and a paper-winding spool, means for driving one of the spools comprising a key-operated cover for said opening, a pinion-driving device directly connected to said cover and turning a driving pinion during movement both forward and backward, and a driven pinion operatively connected to said paper winding spool to turn it in one direction.

19. In a voting machine, the combination

of a plurality of indicators, a movable paper support, a platen, and mechanism intermediate each indicator and the support, said mechanism comprising a pinion and a driving connection between said pinion and each indicator.

20

In testimony whereof, I have signed this specification in the presence of two subscribing witnesses.

CHARLES H. OCUMPAUGH.
